Patented Feb. 10, 1914.

UNITED STATES PATENT OFFICE.

DUFF C. LAW, OF ROXBORO, PENNSYLVANIA, ASSIGNOR TO AMERICAN ARTOGRAPH COMPANY, OF PHILADELPHIA, PENNSYLVANIA, A CORPORATION OF PENNSYLVANIA.

FILM-PERFORATING DEVICE FOR MOVING-PICTURE-TAKING MACHINES.

1,086,376.

Specification of Letters Patent.

Patented Feb. 10, 1914.

Application filed April 18, 1911. Serial No. 621,893.

To all whom it may concern:

Be it known that I, DUFF C. LAW, a citizen of the United States, residing at Roxboro, county of Philadelphia, State of Pennsylvania, have invented a new and useful Film-Perforating Device for Moving-Picture-Taking Machines, of which the following is a specification.

My invention consists of improved means 10 in a moving picture taking machine for perforating a film in perfect register with the images produced upon the same.

It further consists of other novel features of construction, all as will be hereinafter 15 fully set forth.

The annexed drawings and the following description set forth in detail, one mechanical form embodying the invention, such detail construction being but one of various 20 mechanical forms in which the principle of the invention may be used.

In said annexed drawings:—Figure 1 represents a vertical section of as much of a moving picture taking machine as will 25 illustrate the punching device and its co-operating parts. Fig. 2 represents a perspective detail view of the feeding cam, the film-guide and the film-punching device. Fig. 3 represents a horizontal section on the 30 line $z-z$ in Fig. 1.

Similar numerals of reference indicate corresponding parts in the figures.

Referring to the drawings, the numeral 1 indicates the casing of the machine, the 35 front wall of which is formed with vertical film-guides, 2, and with an exposure opening, 3, in which a suitable camera may be secured within a casing, 54, surrounding the exposure opening. A door, 47, is supported 40 upon the front-wall of the casing and has a glass-plate, 55, loosely supported in it and held against the film, 4, sliding in the guides by means of a spring, 56. The sensitive film is fed from a suitable reel (not shown), 45 and passes down along the film-guides, being held by the glass-plate in the door. A shaft, 26, is journaled in the machine frame and has a hand-crank, 27, for turning it. A cog-wheel, 28, is secured upon said shaft 50 and meshes with a pinion, 32^x, which meshes with a pinion, 35, upon the shaft of which is secured a roller, 63, having peripheral teeth at its ends. The film passes around said roller and is held against the same by

a curved spring-arm, 64. The pinion 32^x 55 meshes with a pinion, 32, upon the shaft, 33, of an eccentric feed-cam 14, having its outer end bent in the direction of its rotation. The shaft of this cam is journaled so that the point of the cam will project during its rotation at the lower ends of the film-guides. Two brackets, 58, are secured at the lower ends of the film-guides to have the feed-cam pass between them, and two punches, 57, slide horizontally in said brackets and have springs, 60, bearing against pins, 59, upon their inner ends to force said punches inward against the peripheries of two eccentrics, 62, upon the feed-cam shaft. 60

When the machine is operated, the sensitized film is passed down in the film-guide, beneath the feed-cam and around the roller to a suitable receiving reel. When the lens of the camera is uncovered and the crank rotated, the feed-cam will at each revolution, pull the film down for the space of one image or exposure, and, as the bulges of the eccentrics upon the feed-cam shaft project diametrically opposite to the feed-cam, 70 said bulges will actuate the punches to perforate the film while the latter is at rest and at equidistant points at each revolution of the cam-shaft, bringing the perforations in exact register with the consecutive exposures. 75 The peripheral teeth upon the roller 63 will 80 engage the perforations in the film and feed the film to a receiving reel or other suitable receiving device. 85

By reason of the feed-cam and the eccentrics being upon the same shaft, absolute 90 accuracy of registration in exposures and perforations will be attained and by exceedingly simple, positive and direct means.

Other modes of applying the principle of the invention may be employed for the mode 95 herein explained. Change may therefore be made as regards the mechanism thus disclosed, provided the principles of construction set forth respectively in the following claims are employed.

Having thus described my invention, what I claim as new and desire to secure by Letters Patent, is:—

1. A machine for taking motion pictures and having a film-guide formed with an exposure-opening, punches supported to traverse the edges of such guide and having means for automatically retracting them, a 100 105

shaft journaled transversely to said film-guide and adjacent said exposure-opening and having means for rotating it, an eccentric feed-cam upon said shaft and engaging the film in said guide to intermittently move it across said opening, and eccentric disks upon said shaft having their bulges projecting oppositely to said feed-cam and engaging the punches.

10 2. A machine for taking motion pictures and having a film-guide formed with an exposure-opening, brackets on opposite edges of said guide, punches slideable in said brackets to traverse the edges of said guide, means

for automatically retracting said punches, a shaft journaled transversely to the ends of said brackets and punches, and having means for rotating it, an eccentric feed-cam upon said shaft and between said brackets and engaging the film in the guide to intermittently move it across the exposure-opening, and eccentric disks upon the shaft engaging the punches and having their bulges projecting oppositely to the feed-cam.

DUFF C. LAW.
